CLAIM

The ornamental design of a “mortise lock translatable status indicator”, as shown and described.

DESCRIPTION

FIG. 1 is a right front top perspective view of the “mortise lock translatable status indicator” shown in a locked state;

FIG. 2 is a front elevational view thereof;

FIG. 3 is a right elevational view thereof;

FIG. 4 is a left elevational view thereof;

FIG. 5 is a bottom plan view thereof;

FIG. 6 is a top view thereof;

FIG. 7 is a right front top perspective view of the “mortise lock translatable status indicator” shown in an unlocked state;

FIG. 8 is a front elevational view thereof;

FIG. 9 is a right elevational view thereof;

FIG. 10 is a left elevational view thereof;

FIG. 11 is a bottom plan view thereof; and,

FIG. 12 is a top view thereof.

The rear view of the “mortise lock translatable status indicator” is not included and forms no part of the design.

The broken lines depict portions of the article that form no part of the claimed design.

1 Claim, 4 Drawing Sheets
